UNITED STATES PATENT OFFICE

2,681,459

HAND PROPELLED WATER VEHICLE

Frank Paquette, Cape de la Madeleine,
Quebec, Canada

Application May 1, 1952, Serial No. 285,506

2 Claims. (Cl. 9—18)

1

This invention relates to toys and more particularly to a novel recreational and exercising device usable in water.

One object of the invention is the provision of a manually propelled water float usable as a recreational device.

A further object of the invention is the provision of a manually propelled water float usable as an exercising device.

Another and more detailed object is the provision of a water float having a manually operable propeller, the whole being usable as a recreational and exercising device.

Yet another object is the provision of a portable collapsible water float having a manually operable propeller, the whole being usable as a recreational and exercising device.

With these and other objects in view that may appear as the description proceeds the invention consists in the novel construction and arrangement of cooperating parts as hereinafter more specifically set forth, claimed and shown in the accompanying drawing forming part of this application and in which:

Figure 1 is a plan view of one embodiment of my invention;

Figure 2 is an enlarged elevational view of the frame of the embodiment shown in Figure 1;

Figure 3 is an elevation of a fastening means used in this embodiment;

Figure 4 is a plan view showing the frame of the embodiment in a folded state, and

Figure 5 is an elevational view of the frame in a folded state.

Referring more in detail to the drawings in which similar reference characters designate corresponding parts throughout the several views it will be seen the invention consists of a float, and a manually operable propulsion means mounted thereon. The float consists of a frame

1 which may be of any suitable cross section and material, but, in the form shown is a wood board adapted for use as a seat, and a flotation mem-

ber 2. A keel piece 3 which may be tapered as shown is rigidly secured to the under surface of the frame 1. The flotation member 2 which in this instance is an inflatable pneumatic tube is detachably mounted on the frame 1 by any suitable fastening means such as the plurality of straps 4. The straps 4 are provided with terminally disposed grommets or snap fasteners 5 and are detachably fastened thereby to suitably formed studs 6 the latter being rigidly secured to any convenient surface of the frame 1, e. g.

the bottom. A propeller shaft 7 having a for-

2

ward terminal pulley 8 and after terminal propeller 9 fixed thereto is revolvably mounted in brackets 10 and 11 which are respectively rigidly secured to the forward and after ends of the keel piece 3. A member 12 of wood or other suitable material is inwardly foldably attached to the forward end of the frame 1 and near one side thereof by a hinge 13 in a manner such that the bottom section of the member 12 is disposable in a cut out 14 formed in the frame 1. The hinge 13 may be secured by any suitable fastening means, e. g. machine screws and nuts. The member 12 may be secured in an upright position relative to the frame by any suitable detachable fastening means, but, in the form shown, is securable by a screw eye 15 and a hook and eye 16. The eye 15 is secured to the base of the member 12 while the hook is freely attached to one side of the frame 1.

20 A shaft 17 having a forward terminal pulley 18 which is vertically alignable with the said pulley 8, is revolvably mounted in the upper end of the member 12. A crank handle 19 having a freely revolvable grip 20 is rigidly secured to the after end of the shaft 17. Bushings 21 and 22 serve as thrust bearings for the pulley 18 and crank handle 19. Similar bushings 23 and 24 are provided on the propeller shaft 7. The pulley 18 may be coupled to the pulley 8 in any suitable manner, but, as shown, is coupled by a rope belt 25.

25 It is believed that the construction and advantages of the invention may be apparent from the foregoing paragraphs taken in conjunction with the accompanying drawings without further detailed description.

30 While the preferred embodiment of the invention has been disclosed it is understood that minor changes in the construction and arrangement of co-operating elements may be resorted to within the scope of what is claimed without departing from the spirit of the invention.

I claim:

35 1. A device of the character described comprising an elongated frame having a plane upper surface forming a seat portion, an inflatable annular tube positioned above the upper surface of said frame and detachably secured thereto, a keel depending from the under surface of said frame, bearing brackets attached to the ends of said keel, a rotatable shaft journaled in said bearing brackets, a propeller mounted on one end of said shaft, a pulley mounted on the opposite end of said shaft, a vertical standard mounted 40 on the end of said frame adjacent said pulley,

a second shaft journaled in the upper end of said standard, a second pulley mounted on one end of said second shaft, an endless cable trained around said first-mentioned pulley and said second pulley, a crank connected to the opposite end of said second shaft, means hingedly connecting said standard to said frame for swinging movement towards said frame, the lower end of said standard being seated in a recess in the end of said frame and projecting below the under surface of the frame, and latching means carried by said frame for engaging the lower end of said standard to secure the standard in an upright position.

2. A device of the character described comprising an elongated frame having a plane upper surface forming a seat portion, an inflatable annular tube positioned above the upper surface of said frame, straps attached to said frame adapted to embrace said tube to detachably secure the tube to said frame, a keel depending from said frame, bearing brackets at each end of said keel, a drive shaft journaled in said bearing brackets, a propeller attached to one end of said drive shaft, a pulley attached to the opposite end of said drive shaft, a vertical standard mounted on the end of said frame adjacent said pulley having its lower end seated in a recess in the end of

said frame and depending below the lower surface of the frame, a hinge connecting said standard to the upper surface of said frame whereby the standard may be swung to fold upon said frame, a latch attached to said frame for engaging the lower end of said standard to secure the standard in an upright position, a crank mounted in the upper end of said standard, a second pulley attached to said crank and driving means connecting said second pulley with said first mentioned pulley.
